UNITED STATES PATENT OFFICE

JAMES H. MOYER, OF COLUMBUS, OHIO, ASSIGNOR TO THE COLUMBUS DENTAL MANUFACTURING COMPANY, OF COLUMBUS, OHIO, A CORPORATION

METHOD OF AND MEANS FOR REPAIRING DENTAL BRIDGework

Application filed December 4, 1930. Serial No. 500,116.

This invention relates to a method of and means for repairing dental bridgework, and particularly to a method of and means for repairing or replacing a broken post on a 5 Trupontic or like tooth bridge without removing the bridge from the mouth of the wearer.

Many fixed bridges are now placed in the mouth with cast inlay abutments, which make it very difficult to remove the bridge in the event of post or tooth breakage without destroying abutments.

One object of my invention is to provide a simple, reliable and efficient method of replacing a broken post on a backing or bridge without the necessity of removing the bridge from the mouth, or of disturbing the abutments, and which method may be employed by a dentist without discomfort to the patient.

20 Another object of the invention is to provide a substitute post member adapted to be applied to take the place of the original post, and a jig for use in properly and accurately forming in the bridge or backing a seat for 25 the substitute post, whereby such seat forming operation may be easily and quickly performed.

The invention comprises a novel method and a novel construction and combination 30 of parts for carrying the invention into practical effect, as hereinafter fully described and claimed, reference being had to the accompanying drawings, in which:—

Fig. 1 is a side elevation of a type of tooth 35 and a backing or bridge of the character described embodying my invention.

Fig. 2 is a rear perspective view of the tooth removed from the backing or bridge.

Fig. 3 is a perspective view of the repaired 40 bridge or backing as it appears prior to the application of the tooth.

Fig. 4 is a front to rear section through the backing or bridge and the tooth applied thereto.

45 Fig. 5 is a section on line $\alpha-\alpha$ of Fig. 1.

Fig. 6 is a view of the staple-shaped repair or replacement post on an enlarged scale.

50 Fig. 7 is a section through the backing or bridge with the repair jig applied thereto,

showing the bridge prior to the first working step of the repair method.

Fig. 8 is a similar view showing the backing or bridge at the completion of the first working step.

55

Figs. 9 and 10 are views of the jig.

Referring now more particularly to the drawings, 1 is a tooth of the character described, having a facing 2, a root portion 3, and a lingual overhung portion 4, which portion 4 is provided with a bearing face 5 arranged at an obtuse or other suitable angle to the lingual bearing face 6 of the facing 2, the incisal edge of said facing being indicated at 7. The tooth portion 4 is provided with a post bore or hole 8 intersecting a slot 9 opening through the face 5, which post hole extends from the lingual side of the part 4 to a point beyond the lingual side of the facing 2 at its point of intersection with the face 5, but terminates short of the labial side of said facing. The post hole and slot extend throughout parallel with each other and with the face 5.

70 The tooth 1 is adapted to be mounted upon a backing or bridge 10, which may be of any suitable form in cross-section, but which, in the form shown, is of triangular cross-section and provided with a lingual face 11 and two labial tooth bearing faces 12 and 13, said faces 12 and 13 being disposed in the same angular relationship as the faces 5 and 6 of the tooth, which faces 5 and 6 of the tooth are adapted to rest respectively against the faces 12 and 13 of the bridge or backing when the 75 tooth is applied thereto. The face 12 of the bridge or backing is commonly provided with a post formed thereon and shaped to fit and interlock with the hole 8 and slot 9 of the tooth part 4.

80 For the purpose of this invention, it is assumed that the original post is broken away or damaged and has been replaced by a repair or replacement post 14 constructed in accordance with the present invention.

90 The repair or replacement post 14 is made of gold or other metal of suitable strength and durability and comprises a U-shaped or staple-like body having a pair of parallel arms 15 and 16 and a return bend or end por-

95

100

tion 17. One of the arms 15 serves as an anchor member to engage the bridge or backing and the other arm and the return bend or end portion 17 as an anchor for the tooth 1. To this end, one of the arms of the staple-like replacement post, as the arm 15, is fitted in an opening 18 formed in the bridge or backing 10 between its faces 11 and 13 parallel with the face 12, while the other arm 16 projects over the face 12 and forms the post proper which engages the bore or hole 8 in the tooth. The slot 9 obviously permits passage of the bend 17 and the sliding interengagement of the post and tooth. In order to adapt the post or staple 14 to be fitted properly in position, and said post and the tooth to be held against any tendency to relative motion on the bridge or backing, the backing is formed at the angle of intersection 19 of its faces 12 and 13 with a groove or recess 19 to receive a part of the return bend 17, the sides of which bend 17 are flattened, as shown, to engage said groove and the post hole and slot in the tooth and form a firm and non-rocking connection between the same. The ends of the arms 15 and 16 when the tooth is applied lie flush with the lingual faces of the bridge and tooth, which latter is, in addition to such mechanical connection, cemented in position.

In the operation of making repairs when a post is broken and the tooth 1 detached, I employ a repair jig 20 of the construction shown in Figs. 7 to 10, inclusive. This jig comprises a substantially U-shaped bracket or frame having a pair of spaced parallel arms 21 and 22 spaced at one end and at the sides to form a bridge receiving opening 23 and connected at the other end by a base or cross wall 24 having at the bottom of the opening 23 a tooth bearing surface 25 inclined to the plane of a tooth bearing surface 26 formed by the inner surface of the arm 21. That portion of the bracket or frame forming the arm 21 is bifurcated to form a slot 27 to engage the rib 28 formed by that part of the broken post left intact with the backing, whereby the bracket or jig is centered in position, and said arm and the adjacent part of the base 24 are cut away or beveled to provide a clearance groove 29 which is intersected by said slot. The arm 22 projects at its free end somewhat beyond the plane of the free end of the arm 21, and such end of the arm 22 has its outer face beveled and the arm is formed with an angularly arranged threaded opening receiving a correspondingly arranged clamping screw 30 provided with a pointed end so disposed as to lie immediately in rear of the center of the arm 21. Formed in the part 24 is a guide bore or passage 31 extending in a plane parallel with the inner face of the arm 21 and communicating at its inner end through the surface 25 with the opening 23 adjacent the base of said arm.

The repair jig is applied for use upon the bridge or backing in the manner shown in Figs. 7 and 8, by slipping it on the bridge so that the bridge will be disposed in the opening 23 with its lingual surface 11 facing the arm 22 and its surfaces 12 and 13 respectively facing and bearing against the arm 21 and face 25 of the jig, whereupon the jig is clamped in position by turning up the claiming screw 30 in an obvious manner. A drill of suitable size to pass through the guide opening 31 and to form the bore is inserted into the guide opening 31, after a drop of oil has previously been inserted therein, and operated by means of a dental engine, while being accurately guided by the opening 31, to form the post hole or opening 18 in the bridge or backing. After this post hole 18 is formed, the jig 20 is detached and then, by means of a small engine operated bur or knife-edged stone, the groove or recess 19 is cut in the backing. A staple-shaped replacement post is then applied in the manner previously described to the backing, the tooth 1 fitted and cemented in place, and any projecting portions of the arms of the replacement post ground off smooth at the back of the repaired bridgework so as to leave no rough surfaces liable to cause injury to the tongue. In practice it is advisable to employ a series of generally three drills of progressively increasing lengths in forming the opening 18 in order to obviate liability of drill breakages in drilling the hard metal of which the bridge is composed.

It will be evident, from the foregoing description, taken in connection with the drawings, that my invention provides a method and a means whereby a dentist may readily and conveniently substitute a replacement post for a broken original post in bridgework of the character described without the necessity of removing the bridge or disturbing its abutments, while at the same time producing a repair job equal in strength and appearance, if not superior, to the original tooth mounting. Also it will be seen that the invention provides a method and means whereby such repairs may be made without altering the construction of the tooth and without altering the construction of the bridge except in the slight manner indicated.

Modifications in the construction of the replacement post and jig, and variations in the method described, may be made, within the scope of the invention as set forth in the appended claims, without departing from the spirit or sacrificing any of the advantages of the invention.

Having thus fully described my invention, I claim:

1. The method of repairing dental bridgework of that character having a mechanical interlocking connection between the bridge and tooth comprising a post upon the bridge

to engage a post hole in the tooth, where the post is broken, without removal of the bridge or injury to its abutments, which consists in forming between the lingual and labial faces 5 of the bridge parallel with its post carrying face a bore, applying to the bridge a U-shaped replacement post by engagement of one of its arms with said bore and so as to dispose its other arm over said post replacement face, and then fitting a tooth upon the bridge and into engagement with said replacement post.

2. The method of repairing dental bridgework of that character having a mechanical 15 interlocking connection between the bridge and tooth comprising a post upon the bridge to engage a post hole in the tooth, where the post is broken, without removal of the bridge or injury to its abutments, which consists in 20 forming the bridge with a post receiving bore extending between its lingual and labial faces parallel with its post carrying face together with a seat groove intersecting one end of said bore, fitting upon the bridge a U-shaped 25 replacement post having a flattened return portion by fitting one of the arms of said post in said bore and disposing the other arm of said post and its return portion so as to respectively overhang the post carrying face 30 and recess of the bridge, and then fitting a tooth upon the bridge and into engagement with said replacement post.

3. In dental bridgework, a bridge having a tooth bearing face and an opening extending 35 between its lingual and labial surfaces adjacent to said tooth bearing face, a U-shaped post having one of its arms engaged with said opening and its other arm overhanging said bearing face, and a tooth fitted on the 40 bridge and engaged with the latter-named arm of the post.

4. In dental bridgework, a bridge having a tooth bearing face and an opening extending 45 between its lingual and labial surfaces adjacent to said face, and also provided in a margin of said face with a groove intersecting one end of said opening, a U-shaped post having one of its arms engaged with said opening and its other arm overhanging said 50 bearing face and provided with a flattened return portion seated in said groove, and a tooth fitted on said bridge and having a post hole therein receiving the second-named arm and the flattened return portion of said post.

55. In testimony whereof I affix my signature.

JAMES H. MOYER.
